Term of patent 14 years

(Cl. D15—11)

FIG. 1.

FIG. 2.

FIG. 3.

FIG. 4.

FIG. 1 is a perspective view of a bench showing my design;

FIG. 2 is a side-elevational view thereof;

FIG. 3 is a front perspective view thereof; and

FIG. 4 is a cross-sectional view taken along plane IV—IV of FIG. 2.

The side opposite to that shown in FIG. 1 is identical to that shown in FIG. 1 and the two sides are parallel. The back of the bench is plain and unornamented.

I claim:

The ornamental design for a bench, substantially as shown and described.
